DIRECTION INDICATOR FOR A BICYCLE

Colin Cameron Smades, 43 Victoria Ave., Milton,
Ontario, Canada

Filed May 6, 1963, Ser. No. 74,746

Term of patent 3½ years

(Cl. D48—32)

FIG. 1 is a reduced perspective view of a direction indicator for a bicycle embodying my new design, with the fragmentary portion of a bicycle and an oppositely disposed indicator shown in broken lines for illustrative purposes only;

FIG. 2 is a rear view of the direction indicator showing my novel design;

FIG. 3 is a top plan view thereof;

FIG. 4 is a left-hand end view of the direction indicator;

FIG. 5 is a right-hand end view thereof; and

FIG. 6 is a side elevational view opposite to that shown in FIG. 2.

The characteristic features of my design reside in the appearance of the diamond-shaped clamp having an L-shaped bracket-plate connected to a laterally-projecting support having a forward arcuate straight edge and an angular rear edge, and the vertical element at the terminal end of the elongated support in its relation to the lower intermediate portion of the conventional egg-shaped lamp housing all as shown.

I claim:

The ornamental design for a direction indicator for a bicycle, as shown and described.
